UNITED STATES PATENT OFFICE.

JOHN D. GREEN, OF TOLEDO, OHIO, ASSIGNOR TO WARREN J. WILLITS
AND EDWARD B. LINSLEY, OF THREE RIVERS, MICHIGAN.

CAR-REPLACER.

SPECIFICATION forming part of Letters Patent No. 741,127, dated October 13, 1903.

Application filed May 27, 1899. Serial No. 718,607. (No model.)

To all whom it may concern:

Be it known that I, JOHN D. GREEN, a citizen of the United States, residing at the city of Toledo, in the county of Lucas and State of Ohio, have invented certain new and useful Improvements in Car-Replacers, of which the following is a specification.

This invention relates to improvements in car-replacers.

10 Car-replacers as heretofore constructed have usually been provided with grooves for engaging the flanges of the wheels to guide them up an incline and deposit them on the rails of the track. In my experience with 15 such devices I have found that the grooves are objectionable, as they do not allow the freedom of motion toward the rails that is desired, and I have also found that they are difficult to construct.

20 The object of my invention is to provide an improved car-replacer in which the grooves are dispensed with, which will replace the cars quickly and efficiently by a suitable guiding-ridge located to the outside from the rail, 25 and to produce a structure so arranged that the wheels of the car as they pass up an incline will be delivered with a rolling action directly onto the rails.

I accomplish the objects of my invention 30 by the devices and means described in this specification.

The invention is definitely pointed out and defined in the claim.

My invention is fully illustrated in the accompanying drawings, forming a part of this 35 specification, in which—

Figure 1 is a perspective view of a section of a railway-track with my improved car-replacer in position. Fig. 2 is a transverse sectional view on a line corresponding to line 2 2 40 of Fig. 1, the railway-tie being shown in full lines. Fig. 3 is a side elevation of one of my improved car-replacers.

In the drawings similar letters of reference 45 refer to similar parts throughout the several views.

Referring to the lettered parts of the drawings, A represents the ties of a railway, and A' A' the rails upon the track.

50 B B' are my improved car-replacers. These

are preferably formed out of heavy sheet-steel in the form illustrated in the drawings, the same being a hollow shell with a curved upper surface to increase the strength. The lower edges are provided with teeth *i i* for 55 engagement in the railway-ties to hold the car-replacers securely in position when in use. The upper surface of each car-replacer is arched, and on the side farthest from the rail is a raised rib C, symmetrical on each 60 end of the car-replacer and the same joining together in a raised point portion C' at one side of the longitudinal center close to the head of the rail.

The replacer B is intended for use on the 65 outside of the rail, and consequently the lowest portion next to the rail is on a level with or slightly above the top of the rail when in use. The replacer B' is to be used between the rails, and consequently made a little 70 lower than the rail, as it only needs to raise the tread of the wheel above the head of the rail. The replacer B has a projecting portion on the rail side which rests directly on the rail-flange, and the replacer is made to 75 come into close contact with the rail on that side to permit the passage of the flange of a car-wheel at that point.

To replace a car, my improved replacers are merely placed upon the ties or guard without any preliminary or additional fastening, and the weight of the car drives the teeth *i i* into the tie, preventing slipping or movement of the same, and as the cars are very heavy they adhere to the replacer as they are 80 drawn forward and climb up the same, and the rib part C, particularly on replacer B', engages the flange and carries the wheel toward the rails. The raised portion C' on the outer replacer strikes the side of the wheel 90 opposite the tread and assists in this particular, although the single rib C on the replacer B' would be sufficient for replacing most car-wheels. The curved form of these car-replacers and their peculiar formation in that 95 connection enables heavier sheet-steel to be used in their manufacture than it is possible to use on those replacers containing grooves. The form I have shown would be effective, however, if the replacers were cast solid in- 100

stead of hollow; but their great weight in this instance would make them objectionable.

Having thus described my invention, what I claim as new, and desire to secure by Letters Patent, is—

A car-replacer consisting of a hollow shell open at the bottom and having a broad base substantially rectangular in form, the lower edge of said shell being provided with teeth to engage the ties and retain the replacer in position, said replacer having a convexly-curved upper portion provided with a rib C on the opposite side from the rail symmetrical at each end of the replacer and curved

inwardly toward the rail at the center joining forming the point C' projecting above the surface and extending close to the rail for the purpose of guiding the car-wheel in such manner that as soon as the wheel is raised to the top of the rail, it will be delivered onto the same, substantially as and for the purpose specified.

In witness whereof I have hereunto set my hand and seal in the presence of two witnesses.

JOHN D. GREEN. [L. S.]
